STEAM BOILING APPARATUS

Carl August Steen, Getinge, Sweden

Application February 26, 1948, Serial No. 11,247
In Sweden January 13, 1947

5 Claims. (Cl. 219—40)

1

This invention relates generally to a steam boiling apparatus, and more particularly to an apparatus comprising range top having a cooking hole for a detachable boiling vessel immersed therein.

One object of the invention is to provide a sealing device for the boiling vessel which firmly prevents leakage of steam between the boiling vessel and the edge of the cooking hole.

Another object is to provide a locking device for the boiling vessel capable of preventing the pressure of the steam in contact with the boiling vessel to rise above a predetermined value.

A further object is to obtain a locking device for the boiling vessel which is easy to operate, which is small and compact and simple in construction.

The accompanying drawing shows, for the purpose of illustrating the present invention, a preferred embodiment in which the invention may take form, it being understood that the drawing is illustrative of the invention rather than limiting the same.

In the drawing:

Figure 1 is a vertical section through the locking device and the sealing device.

Figure 2 is a plan view of the locking device.

Figure 3 is a side view thereof.

Figure 4 is a small scale vertical sectional view through one of the cooking wells, illustrating the general organization of parts.

The steam boiling apparatus, illustrated in the drawing is provided with a range top having one or more cooking holes 15 therein, the edges 10 of which are engaged by a sealing ring 11 of rubber or other elastic material. A boiling vessel 12 provided with an outstanding flange 13 is inserted in the cooking hole 15 illustrated and rests with its flange 13 on the sealing ring 11, against which the flange is pressed by a rotary pawl 8 formed as a lifting hook. As indicated in the drawing by the wall 14 welded to the under side of the range top 1 a steam jacket 14 encloses the cooking vessel, and the steam may be generated therein by electrodes 16 in water or may be supplied from the outside.

A tube 2 passing through the range top 1 and welded thereto has its main portion beneath the range top. The portion extending above the top is threaded on the outside as at 2' and is provided with a cover 3 provided with interior screw threads 3' which by means of a wrench may be drawn tight and thereby locked against the top. The cover 3 has a central opening which forms an upper slide guide for a spindle 4 with a sleeve

2

5. A washer 6 on the spindle exerts a pressure against the sleeve by means of a nut 7, and the sleeve presses the rotary pawl 8 against the countersunk head of the spindle 4. Two helical springs 9 in the tube 2 rest with the ends against the washer 6 and the cover 3 thereby pressing the rotary pawl downwards against the flange 13. The rotary pawl may thus be turned round together with the spindle to be resiliently moved over the flange so that this is pressed against the sealing ring with a pressure determined by the springs. When the pawl 8 is lifted the washer 6 serves as the lower guide of the spindle 4.

The pressure of the springs is adjusted to resist the normal pressure on the boiling vessel, but if the steam pressure by any occurring fault should rise to an injurious value the rotary pawls are lifted by the steam so that the excess of steam may escape thereby preventing accidents and damage to the boiling apparatus.

I claim:

1. An electric steam boiling apparatus, comprising a range top having an opening therein, a steam jacket secured to the lower surface of said top, a removable boiling vessel having a flange extending laterally from its side wall, said vessel extending through said opening in said top into said steam jacket, steam generating electrodes mounted in said steam jacket, a sealing ring of an elastic material extending along the edge of the opening of said top and having an inwardly directed sealing flange adapted to be pressed by the steam pressure against the lower surface of said projecting flange, a plurality of pawls each mounted on a vertical, slidably and turnably mounted spindle and adapted to be turned over said projecting flange, said shaft passing through said top and being spring-loaded so as to press the pawl against said projecting flange.

40. 2. An electric steam boiling apparatus, comprising a range top having an opening therein, a steam jacket secured to the lower surface of said top, a removable boiling vessel having a flange extending laterally from its side wall, said vessel extending through said opening in said top into said steam jacket, steam generating electrodes mounted in said steam jacket, a sealing ring of an elastic material extending along the edge of the opening of said top and having an inwardly directed sealing flange adapted to be pressed by the steam pressure against the lower surface of said projecting flange, a plurality of pawls each mounted on a vertical, slidably and turnably mounted spindle and adapted to be turned over said projecting flange, said shaft passing through

said top, a spring casing for each pawl secured to and extending below said top for receiving said spindle, and a helical spring encompassing said spindle within said casing for pressing the appending pawl against said projecting flange.

3. An electric steam boiling apparatus, comprising a range top having an opening therein, a steam jacket secured to the lower surface of said top, a removable boiling vessel having a flange extending laterally from its side wall, said vessel extending through said opening in said top into said steam jacket, steam generating electrodes mounted in said steam jacket, a sealing ring of an elastic material extending along the edge of the opening of said top and having an inwardly directed sealing flange adapted to be pressed by the steam pressure against the lower surface of said projecting flange, a plurality of pawls each mounted on a vertical, slidably and turnably mounted spindle and adapted to be turned over said projecting flange, said shaft passing through said top, a spring casing for each pawl secured to and extending below said top for receiving and guiding said spindle, and a helical spring encompassing said spindle within said casing for pressing the appending pawl against said projecting flange, said spring bearing at its upper end against a fixed portion of the spring casing and at its lower end against a lug on the spindle.

4. An electric steam boiling apparatus, comprising a range top having an opening therein, a steam jacket secured to the lower surface of said top, a removable boiling vessel having a flange extending laterally from its side wall, said vessel extending through said opening in said top into said steam jacket, steam generating electrodes mounted in said steam jacket, a sealing ring of an elastic material extending along the edge of the opening of said top and having an inwardly directed sealing flange adapted to be pressed by the steam pressure against the lower surface of said projecting flange, a plurality of pawls each mounted on a vertical, slidably, and turnably mounted spindle and adapted to be turned over said projecting flange, said shaft passing through said top, a spring casing for each pawl extending through the top and fastened thereto, a cover for said spring casing threadedly engaged with the upper portion of the spring casing above the top, said cover having a central opening serving as a guide for said spindle which passes through said opening into said spring casing, a helical spring encompassing the spindle, and a lug on said

spindle, said spring bearing at its upper end against said casing cover and its lower end against said lug.

5. An electric steam boiling apparatus, comprising a range top having an opening therein, a steam jacket secured to the lower surface of said top, a removable boiling vessel having a flange extending laterally from its side wall, said vessel extending through said opening in said top into said steam jacket, steam generating electrodes mounted in said steam jacket, a sealing ring of an elastic material extending along the edge of the opening of said top and having an inwardly directed sealing flange adapted to be pressed by the steam pressure against the lower surface of said projecting flange, a plurality of pawls each mounted on a vertical, slidably and turnably mounted spindle and adapted to be turned over said projecting flange, said shaft passing through said top, a spring casing for each pawl extending through the top and fastened thereto, a cover for said spring casing threadedly engaged with the upper portion of the spring casing above the top, said cover having a central opening serving as a guide for said spindle which passes through said opening into said spring casing, a helical spring in said spring casing encompassing the spindle, and a sleeve on said spindle pressing the pawl against an upper head of the spindle by means of a nut on the lower end of the spindle, said spring bearing at its upper end against said casing cover and at its lower end against said nut.
